UNITED STATES PATENT OFFICE.

CASIMIRO GINESI, OF WASHINGTON, DISTRICT OF COLUMBIA.

LETTER-BOX.

SPECIFICATION forming part of Letters Patent No. 244,227, dated July 12, 1881.

Application filed May 2, 1881. (No model.)

To all whom it may concern:

Be it known that I, CASIMIRO GINESI, a citizen of the United States, resident at Washington, in the county of Washington, District of Columbia, have invented certain new and useful Improvements in Letter-Boxes; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

Figure 1 represents a front view of the box and bag attached, the lids of the recesses open. Fig. 2 is a transverse section. Fig. 3 is a longitudinal section of part. Fig. 4 is a bottom view of the box. Fig. 5 is a top view of the bag, key-stud in section; Fig. 6, enlarged front of bag, parts broken away; Figs. 7 and 8, views of the lock; Fig. 9, the guard; Fig. 10, enlarged detail; Fig. 11, the dial; Figs. 12 and 13, key-catches; Fig. 14, enlarged section.

This invention relates to improvements in mail-boxes.

The object of the invention is the production of a device whereby the carrier is prevented from tampering with the mail-matter and the time of collection indicated, the latter forming a detector.

To these ends the invention consists in a box of peculiar construction, and in combination therewith a bag having certain features, all as hereinafter fully set forth.

In the annexed drawings, the letter *a* indicates a mail-box of any desirable shape and size, the ordinary curved-top one being preferable, having the bottom open, as at *b*. To the rear side of this opening *b* are secured two parallel strips of metal, *c* *c*, having a narrower one, *c'*, between their outer edges, leaving a space, *c''*, between their inner ones, said strips thus forming a guideway; or a single piece of metal having a guide-groove on its inner edge may be used.

Fastened to the front side of opening *b* is a casing, *d*, flush with the bottom, and having the deep securing-flange *d'* extending into the box. On its inner face this casing has secured to it the two parallel longitudinal flanges *e* *e'*, forming a groove or space, *e''*, in the plane of groove or space *c''* on the opposite side, the in-

ner flange, *e'*, having two angular notches, *e'''* *e''''*. At these notches the casing *d* is provided with angular perforations *e''* *e'''*, extending from flange *e* across groove *e''* and beyond flange *e'*, as shown at *e''''*.

Seated in casing *d* about mid-length is a lock, *f*, the catches *f'* *f''* of which project through the perforations *e''* *e'''*. This casing *d* has the projecting lip *g*, which bears against the frame of the box *a*, and within said lip there is formed in the casing the key-hole *g'* for the locking, there being a notch, *g''*, for admission to said hole. Hinged to one side of this notch is the guard *h*, to which is pivoted a slide-rod, *h'*, which passes lengthwise through casing *d*, and, projecting beyond, has the catch-head *h''*, having the bevel *h'''* toward the edge of the bottom, to which the casing is fastened, said rod having a spring, which keeps the rod thrown out and the guard down. This head *h''* is turned down at an angle to the stem of the rod, and secured to the bottom of the box at the ends are flanges *h* *h'*, the former in the plane of the head *h''*, forming guide-grooves *h''*; or said grooves may be simply scored in the ends of the box, which extend far enough down for that purpose.

In one end of the box, preferably that away from the catch-head *h''*, is made a transverse slit, *l*, leading into the opening *b* on a line with grooves *c''* *c'''*. This slit is faced with a strip of metal, *m*, having registering-slit *m'* and depending flange *m''* parallel to the flange *h*, but spaced therefrom at *m'''*, there being a corresponding strip, *m''*, at the other, spaced at *m''''* from flange *h'*. Passing through these slits is a plate, *n*, having inside the box *a* the depending lip *n'*, and outside the upturned catch *n''*. This plate has secured upon its upper face, at one edge, the three bars *n''''*, with spaces *n'''* between each two, said plate being the width of the opening *b*, and its edges coming in the grooves *c''* *c'''*, the spaces *n'''* registering with perforations *e''* when the plate is in place, which thus forms the bottom of the box, on which plate the mail-matter rests, the catches *f'* *f''* hooking in spaces *n'''*, holding the plate securely in place.

On each side of notch *g''* there are secured to the bottom edge of the box two bearing-plates, *o* and *p*, in which are pivoted lids *q* and *r*, which are provided with guide-lugs *q'* *r'*, catches

$q^2 r^2$, springs $q^3 r^3$, and close openings s and t in the side of the box, which said openings lead into recesses $s' t'$.

Forming a part of lock f is a bar, p' , running lengthwise of casing d , and having a hooked end, p^2 , coming into recess s' , and a straight tongue, p^3 , into recess t' , in which latter recess is a plate, t^2 , having notch t^3 , across which notch the tongue extends, being held out by the spring in the bar p' .

In recess s' is secured a spring, s^2 , having a notched swinging head, s^3 , the position of this head and that of notch t^3 being such as to engage the catches on the lids q and r . The bar p' , when in a locked position, has its hook p^2 and tongue p^3 also in position to engage the catches, and when it is in this position and the lids are closed spring s^2 is forced back and the catch q^2 is held between said spring and the hook p^2 , and catch r^2 forces tongue p^3 against its spring of bar p' until the catch-head passes, when the spring throws the tongue into engagement. This bar p' , as stated, is a part of the device of the lock, and when the latter is opened, so as to release catches f' from spaces n^4 , the said bar is shot, releasing the lids and allowing their springs $q^3 r^3$ to throw them open.

In recess s' is placed a key, s^4 , the use of which will be hereinafter explained, held by a chain, s^5 , preferably fastened to the lid q .

In recess t' is placed a dial, having on its face the hours and parts thereof, arranged so that only a portion is to be shown at one time, such dial to be movable, so as to bring into the field the desired number. This dial may also have any proper legend—such as “Time for next mail,” or “Carrier will call”—arranged so as to come at the exposed number. The lid to this recess should be transparent, so that the dial can be seen from the outside. This operates as a detector, for the carrier is to change the number for the next round each time he empties the box, and if the time of inspection be later than that on the dial it will indicate that the carrier has failed in his duty. In this way any depositor can tell when his letter or package is to be taken out, and also whether, after deposit, it has been taken out at the proper time.

u represents the bag to be carried by the carrier for emptying the box described. This bag is secured to a metallic frame, u' , of a size corresponding to the bottom of box a , which said frame has at each end the flanges u^2 , forming guide-grooves u^3 , open at one end and having stops u^4 at the other, one groove having the bevel-tongue u^5 . The sides and one end of this frame have guide-grooves $u^6 u^7$, and the other end has the slot u^8 in the plane of these grooves. Passing through this slot u^8 and into the grooves $u^6 u^7$ is a cover-plate, v , having inside lip, v^1 , outside catch, v^2 , and edge bar, v^3 , with space v^4 .

To one side of the frame u' is secured a spring-lock, w , the catch of which, w' , engages in space v^4 of bar v^3 , the key contained in re-

cess s' being for this lock and adapted to the hole w^2 . No other key except the master-key kept at the office can open the bag.

At the key-hole w^2 there is formed on the frame u' a lug, x , corresponding to notch g^2 , having the outwardly-projecting hollow stud x' , through which and the lug x passes a key, y , having handle y^3 outside and wards y^4 inside, said key being surrounded by a spring, y^2 , inside of stud x' , which tends to force the key inward. It will be seen that by this construction the key of the box is secured to the bag and that of the bag to the box; hence to separate the two parts the keys must be removed from their respective locks. This, however, must not be allowed until the slides are in, so that the keys may not be removed until the receptacles are securely closed.

In Figs. 12 and 13 are shown locking-dogs for catching the keys, preventing the movement of the latter until the slides are in position, when such dogs are held off and the keys loosened.

a^4 is a lever, the head b^4 of which projects through slot n^5 into the interior of the box in the end of groove e^2 , said rod being operated by a spring, p^4 . This rod a^4 engages the heel g^4 of an elbow-lever, n^4 , the head s^6 of which is adapted to catch the key y' . As soon as catches f' are withdrawn from notches n^4 and the slide n is withdrawn the spring p^4 throws the head s^6 so as to clutch the key y' , which will be kept held until the slide n is shoved home, when the inner end of the end bar, n^3 , striking head b^4 , will release the elbow-lever from the key y' , when the latter can be turned to be taken out; but this locks the slide n .

z^5 is a dog pivoted in lock w , and held in by spring y^5 to engage key s^4 . This dog is thrown off by the beveled lug y^6 on the slide v bearing on the beveled heel x^5 of said dog, which happens when the slide is in position. When the slide is withdrawn the dog is released and catches the key.

When the box a is to be emptied the frame u' is slipped onto the bottom, the flanges u^2 engaging the flanges $k k'$, and when the bevel u^8 strikes the head h^2 the guard h is swung up and the wards y' of key y enter the lock f . As this lock f is unlocked the catches $f' f'$ are withdrawn from spaces n^4 , loosening the bottom plate, n , and the bar p is shot, lids s and t falling. This exposes key s^4 , by which the lock w is unlocked, which loosens the top plate, v , when both plates can be drawn out, and the mail-matter will drop into the bag. For convenience in handling, it is better that the plate v of the bag should come out at the side opposite to that of the plate n . As the plates are drawn out the keys are caught as before described. When the exchange of mail-matter is made the slides are returned, the dial changed for the next trip, locks fastened, and the parts separated.

The lid r need not be made to be opened, and the dial will be made automatic, as shown

in Fig. 11, where it is operated by a pawl, t^7 , attached to the slider-bar p^3 .

This device is applicable not only to mail-boxes, but also to money-boxes in cars, &c.

5 I claim—

1. A delivery-box having a sliding bottom, in combination with a detachable bag or receiver having a sliding top, and mechanism, substantially as described, whereby the one is 10 enabled to act on the other, as set forth.

2. A delivery-box having a recess for holding the key of the bag, another recess having a dial, and a lock, whereby both recesses are simultaneously opened.

15 3. A delivery-box and receiving-bag, each

having the key of the other, and a closing slide, in combination with means, substantially as described, whereby the keys cannot be released until the slides are in position, as set forth.

4. A delivery-box having a pivoted key-hole 20 guard, in combination with a bag adapted to the box, and means, substantially as described, for moving the guard to admit a key attached to the bag, as set forth.

In testimony whereof I affix my signature 25 in presence of two witnesses.

CASIMIRO GINESI.
